UNITED STATES PATENT OFFICE

2,182,907

AUTOMATIC FIREARM

Heinrich Vollmer, Biberach-Riss, Germany, assignor to Gustav Genschow & Co. Aktiengesellschaft, Berlin, Germany, a company of Germany

Application May 31, 1938, Serial No. 211,049
In Germany May 31, 1937

2 Claims. (Cl. 42—3)

A known method of regulating the speed of discharge of automatic firearms consists in providing the weapon with a pneumatic brake which can be put into operation so as to retard the movement of some reciprocating part of the firearm operative in connection with the discharge, so that with the brake mechanism in operation the rate of discharge is lower than when that mechanism is put out of action.

5 According to my invention the brake mechanism, which includes a plunger operating in a pneumatic brake cylinder, is associated with a pawl which is connected to the plunger and is adapted, when free to act, to engage the reciprocating part of the firearm mechanism so that the plunger retards the movement preceding the discharge of a shot, the pawl being, however, automatically disengaged from the reciprocating part when the required retardation 10 has been effected.

10 According to my invention the brake mechanism, which includes a plunger operating in a pneumatic brake cylinder, is associated with a pawl which is connected to the plunger and is adapted, when free to act, to engage the reciprocating part of the firearm mechanism so that the plunger retards the movement preceding the discharge of a shot, the pawl being, however, automatically disengaged from the reciprocating part when the required retardation 15 has been effected.

15 For rendering the brake mechanism inoperative, so that the rate of discharge is normal, the pawl may be put out of operation by means of a manually controlled catch which prevents it from engaging the reciprocating member referred to.

20 The brake mechanism may be a detachable unit which can be fixed to the weapon by a simple operation, with the pawl in position to engage the reciprocating member.

25 An embodiment of the invention is shown by way of example in the accompanying drawing, in which—

Fig. 1 is a side view, with a portion of the stock removed.

Fig. 2 being a plan view of the brake mechanism, in the operative position, and

Fig. 3 a plan view of the same in the inoperative position.

30 Figs. 4 and 5 are end views of the mechanism, and

Fig. 6 is a section on the line A—B of Fig. 4.

Fig. 1 shows part of the stock 1 and trigger guard 2, and the clasp 3 holding the rear end 45 of the barrel tube 4 or chamber. The cartridge feed casing 5 has at the rear a narrow lug 6.

Between the stock 1 and the cartridge feed casing 5 is a brake cylinder 7, which has two cheeks 8, 9 fitting against the under part of the barrel tube 4. This part of the barrel has a recess 32 for entrance of one arm of a pawl 10 adapted to coact with a reciprocating part of the firearm. This may be the chamber 30, but where the barrel reciprocates it may be the barrel 50 or a tube fixed thereto. In the embodiment

illustrated the chamber 30 sliding in the tube 4 has at the bottom a recess 31 or an abutment for engagement with the pawl.

The cylinder 7 has at the rear two lugs 11, between which the lug 6 of the casing 5 engages. The lugs have holes enabling the cylinder to be fixed to the firearm by means of bolts 12, no other fastening being required.

The axis of the cylinder 7 is slightly inclined to that of the tube 4, and the cylinder has there- 10 in a plunger 13 urged rearwards by a coiled spring 14. The cylinder is closed at the rear by a head 15, which is screwed into it and has vent holes 16 and also a central hole for the plunger rod 17. The cylinder head at the other end 18 has a small vent hole 18, the effective size of which may be regulatable.

Between the cheeks 8 and 9 the wall of the cylinder has an external guide channel 19 for a slide 20, which has an arm 21 fixed by a nut 22 to the plunger rod. The slide has a recess in which the pawl 10 is mounted on a pivot 24, and a spring 25 acts on the pawl so that the tip of the pawl is urged out of the recess, and the tail 10¹ of the pawl is pressed against the 25 bottom of the recess (Fig. 6).

When recoil causes the chamber to slide to the rear the pawl is first depressed and the recess or abutment at the under part thereof then engages the pawl, so that when the chamber moves forward again the slide 20 and plunger 13 move with it, the movement of the chamber being braked by the plunger. Owing to the inclined position of the cylinder the pawl recedes from the chamber during this movement, and is 30 thereby at a certain point automatically disengaged therefrom, allowing the chamber to continue its movement, without brake action, for completing its part of the action which produces discharge.

40 The cheek 9 has a slotted guideway for a slide having a handle 27 on the outside of the cheek and a nose 28 on the inside. The pawl 10 has a pin 29 projecting laterally therefrom into the path of the nose 28, so that when the handle 45 is pulled to the rear, into the position shown in Fig. 3 the nose engages over the pin and depresses the pawl, so that the pawl cannot engage the chamber. A projection 28¹ on the nose limits the extent to which the slide can be pulled 50 back. With the handle in the position shown in Fig. 2 the pawl is thrust out of the recess 28 by the spring 25, as shown in Fig. 6.

What I claim as my invention and desire to secure by Letters Patent of the United States is: 55

1. An automatic firearm having in combination a firing mechanism including a member making a reciprocating movement operative for each discharge, a pneumatic brake comprising a cylinder and plunger therein, and a pawl connected to said plunger, adapted temporarily to engage said reciprocating member during the movement of said reciprocating member preceding each discharge, so that brake action is applied to said movement by said plunger, the axis of said cylinder being inclined to the path of said reciprocating member so that said pawl recedes from said member while moving in engagement therewith, and is thereby moved out of engagement.

2. An automatic firearm having in combination

firing mechanism including a member making a reciprocating movement operative for each discharge, a pneumatic brake comprising a cylinder and a plunger therein, said plunger having a rod projecting from said cylinder, a slide slidable on said cylinder, parallel with the axis thereof, means connecting said slide to said plunger rod, for reciprocating said slide, and a pawl mounted on said slide, adapted temporarily to engage said reciprocating member of said firing mechanism during the movement of said reciprocating member preceding each discharge, so that brake action is applied to said movement by said plunger.
